UNITED STATES PATENT OFFICE.

JOHN NYLANDER, OF MUSKEGON, MICHIGAN.

PROPELLER.

Application filed April 16, 1923. Serial No. 632,514.

To all whom it may concern:

Be it known that I, JOHN NYLANDER, a citizen of the United States, residing at Muskegon, in the county of Muskegon and State of Michigan, have invented certain new and useful Improvements in Propellers; and I do declare the following to be a full, clear, and exact description of the invention, such as will enable others skilled in the art to which it appertains to make and use the same.

My invention relates to improvements in boat propellers and has for one object to provide a propeller provided with a novel form of blade which may be quickly and easily detached if injured, so that another may be easily substituted.

A further object is to provide a construction in which part of the attaching means for the removable blade, acts as a key to prevent relative rotation of the propeller hub and the shaft which extends therethrough.

Another object of the invention is to provide a propeller which will not form a vacuum pocket in the water when operating.

With the foregoing in view, the invention resides in the novel subject matter herein-after described and claimed, the description being supplemented by the accompanying drawing.

Figure 1 is a side elevation of a propeller constructed in accordance with my invention.

Figure 2 is a sectional view on line 2—2 of Fig. 1.

Figure 3 is a rear end elevation.

Figures 4 and 5 are transverse sectional views on lines 4—4 and 5—5 of Fig. 1.

Figure 6 is a longitudinal sectional view as indicated by line 6—6 of Fig. 3.

In the drawing above briefly described, the numeral 1 designates an axially elongated hub which is provided with a stepped bore 2 in which the similarly shaped rear end of the propeller shaft 3 is secured by a nut 4 contacting with the rear end of the hub. At diametrically opposite points, the hub 1 is formed with relatively large

radial sockets 5 which extend to the bore 2 adjacent one of the shoulders, 3^a provided by the stepped formation of the shaft. A pair of smaller sockets 6 are formed in said hub at opposite sides of each of the sockets 5.

A pair of helical blades 7 are provided with curved inner edges 8 contacting with

opposite peripheral portions of the hub 1 and each of said edges is provided with a relatively large and long stud 9 and with a pair of smaller studs 10, said studs 9 and 10 being received in the sockets 5 and 6 respectively. The studs 9 have their inner ends shaped to fit against the shaft 3 and said studs are snugly received in depressions of seats 3^b formed in the shoulder 3^a. The studs 9 are formed with openings 11 which align with longitudinal bores 12 formed in the hub 1, screws 13 being received in said bores and openings as clearly shown in Fig. 2, for the purpose of holding the blades 7 detachably in place and retaining the studs 9 in the seats 3^b, so that they will key the hub 1 to the shaft 3 and prevent possible relative turning. If either of the blades should become damaged, it is an easy matter to remove the proper screw 13 and detach the blade, whereupon a new one may be easily substituted. Normally, however, the nut 4 partly covers the screws 13 and prevents accidental removal thereof.

I have found that the best results are obtained by circumferentially elongating each of the blades 7 for approximately 180°, securing said blades to the hub 1 centrally between their ends, and positioning the outer peripheral edges of the blades in concentric relation with the axis of said hub.

In connection with the features above described, I prefer to form a plurality of ports 14 longitudinally through the hub 1 and experience has proven that these ports will prevent the propeller from forming a vacuum pocket in the water when it is in operation. Thus, much better results may be obtained than by the use of the ordinary propeller and I have found that approximately twenty-five per cent power increase is obtained by the use of the construction herein disclosed.

On account of the proven advantages thereof, the present disclosure may be considered as the preferred form of my invention, but it is to be understood that within the scope of the invention as claimed, numerous minor changes may be made.

I claim:

1. A propeller comprising a hub provided with a plurality of radial sockets, a propeller blade having its inner edge contacting with the outer surface of said hub, studs projecting inwardly from the inner edge of said blade into said sockets, and means engaging

- one of said studs to secure said blade to said hub.
2. A propeller comprising a cylindrical hub having a relatively large radial socket and smaller sockets at opposite sides of said relatively large socket, said hub also having a longitudinal off-center bore which intersects said relatively large socket, a pitched blade having a curved inner edge contacting obliquely with the peripheral surface of said hub and having relatively large and small studs received in the aforesaid sockets, the relatively large stud having an opening aligned with said bore, and a screw received in said bore and passing through said opening to detachably connect the blade and hub.
3. A propeller comprising a hub having a shaft receiving bore, a pitched blade contacting with said hub and having a stud extending through the hub from the periphery of the latter to a point spaced between the axis of said bore and the wall of the latter, the inner end of said stud being adapted to engage a propeller shaft when the latter is inserted in said bore.
4. A propeller hub having a longitudinal bore and a radial socket from said bore to the periphery of the hub, a pitched blade contacting with the hub and having a stud extending through said radial socket and projecting slightly beyond the wall of said bore, and a shaft secured in said bore, said shaft having a seat receiving the projecting inner
- end of said stud to hold the shaft and hub against relative rotation.
5. A propeller hub having a longitudinal bore and a radial socket from said bore to its periphery, a pitched propeller blade contacting with the hub and having a stud projecting through said socket and extending slightly beyond the wall of the bore, and a shaft secured in said bore, said shaft being of two diameters to provide a shoulder at the juncture of such diameters, said shoulder being cut away to form a seat snugly receiving the projecting inner end of the stud to hold the hub and shaft against relative turning.
6. A propeller hub having a longitudinal shaft-receiving bore, and a radial socket opening through its periphery, a pitched propeller blade having a stud received in said socket, said stud and hub having aligned bores, a removable pin received in said aligned bores to secure the propeller blade in place, the rear end of said pin being flush with the rear end of the hub, a propeller shaft passing through the shaft-receiving bore of said hub, and a nut threaded on the rear end of said shaft, said nut engaging the rear end of said pin to prevent accidental removal thereof.

In testimony whereof I have hereunto affixed my signature.

JOHN NYLANDER.
